HOLDER

Lazzaro V. Villani, Milford, Mass.

Application January 14, 1936, Serial No. 59,151

1 Claim. (Cl. 292—76)

This invention appertains to new and useful improvements in holders and more particularly to a holder of the type especially adapted for holding doors against walls.

5 The principal object of the present invention is to provide a holder of simple construction which can be readily secured in place on a wall or wall baseboard and a door without in the least detracting from the appearance of either.

10 Other important objects and advantages of the invention will become apparent to the reader of the following specification.

In the drawing:

Figure 1 represents a longitudinal sectional view through the assembly.

Figure 2 represents a cross sectional view taken substantially on line 2—2 of Figure 1.

Figure 3 represents a front elevational view of the socket structure.

20 Referring to the drawing wherein like numerals designate like parts, it can be seen that the socket structure generally referred to by numeral 5 consists of a shell 6 having pressed in portions 7 extending longitudinally thereof at equal

25 circumferentially spaced intervals to define pockets 8 for the reception of the spring fingers

9. Each of these spring fingers is secured at one end as at 10 to the inside of the shell 6 by welding or some other suitable means or method. The 30 opposite end portion of each of these spring fingers 9 is bent laterally as at 11 and then backwardly as at 12 with an outwardly curved extremity 13.

These outwardly curved extremities 13 converge 35 toward each other in the manner shown substantially in Figure 1. These fingers are of spring material and form a constricted passageway in

alignment with the opening 14 in the front of the shell 6.

For securing the socket shell 6 to a wall or baseboard, a screw 15 is provided which projects through an opening in the rear end of the shell 5 from a head structure 16 which is of cup formation to retain the resilient bumper 17 against which the male member 18 can strike. This male member 18 has its head portion gradually enlarging toward its outer end where it curves off in a 10 hemi-spherical shape. The opposite end is provided with a screw 19 which is to be driven into a door.

Obviously when the socket member and the male member 18 are properly placed on a baseboard and a door, when the door is opened and moved toward the baseboard, these two parts will engage and retain the door in open position.

While the foregoing specification sets forth the invention in specific terms, it is to be understood 20 that numerous changes in the shape, size and materials may be resorted to without departing from the spirit and scope of the invention as claimed hereinafter.

Having thus described the invention, what is 25 claimed as new is:

A keeper of the character described comprising a shell open at one end, a fastener projecting from the opposite end of the shell, inwardly disposed and longitudinally extending depression 30 in the shell defining troughs between the same, elongated strip spring members snugly disposed in the troughs and having their ends adjacent the opening bent backwardly, the free ends of the backwardly bent forces being disposed in con- 35 verging relation.

LAZZARO V. VILLANI.
